UNITED STATES PATENT OFFICE.

WILLIAM W. VOSPER, OF TOLEDO, OHIO, ASSIGNOR TO THE TOLEDO PIPE THREADING MACHINE COMPANY, OF TOLEDO, OHIO, A CORPORATION OF OHIO.

DIE HEAD.

Application filed June 28, 1924. Serial No. 722,905.

This invention relates to thread cutting tools, and particularly to one of the hand type having a plurality of thread cutting sets carried in operative relation thereby, although it is not restricted to use in this connection.

The object of the invention is the provision of a light and compact tool of the class described, and which has its chaser mounted in a strong and durable manner and capable of being easily and quickly removed and others substituted therefor.

The invention is fully described in the following specification, and a preferred embodiment thereof illustrated in the accompanying drawings, in which,—

Figure 1 is a side elevation of a device embodying the invention, and Fig. 2 is a section thereof on the line 2—2 in Fig. 1.

Referring to the drawings, 1 designates a die head having three equidistantly spaced work-receiving holes 2, 3 and 4 extending diametrically therethrough in intersecting relation with each terminating at one end in an enlargement 5 concentric therewith and disposed in a respective boss 6 provided on the respective side of the die head. The bosses 6 are equidistantly spaced circumferentially around the head and small ends of the holes 2, 3 and 4, which are disposed in opposition to the respective enlarged ends 5 thereof, terminate between the bosses, as shown. The interior of the head 1 is preferably hollowed out, as shown at 7, to provide lightness of construction and is provided at opposite sides thereof at right angles to the circumferential plane of the holes 2, 3 and 4 with oppositely projecting socketed extensions 8 for receiving handles 9 to facilitate a turning of the head about a pipe or work piece as an axis, inserted in any one of said holes.

The outer end of each boss 6 forms an annular ring seat 10, which in width extends from the outer edge of the boss to near its inner edge, being spaced from the respective hole enlargement 5 by an annular shoulder or flange 11 that is concentric to said enlargement. The portion of each boss 6, which forms the wall of its bore enlargement 5, is provided with a plurality of radial chaser receiving slots or openings 12, four in number in the present instance, which extend radially entirely through the

wall and, in depth extend inward a distance 55 from the outer end of the respective boss to suit the depth of the chasers 13 disposed therein. Each chaser 13 extends from the outer end of its opening 12 to a distance 60 within the respective opening enlargement 5 to adapt them to have threading engagement 65 at their inner ends with their work piece projecting through the opening 5. A chaser clamping ring 14 is mounted on the outer end of each boss in close fitting relation around the shoulder 11 thereof, by which it is retained in concentric relation to the boss center and is adapted to seat on the outer side edges of the chasers 13 to hold them firmly in the openings 12 provided 70 therefor, the chasers projecting slightly above the ring seat 10 to permit the ring to have a firm clamping action thereagainst thereby to enable the ring to assist in counteracting the thrust of the chasers. Screws 75 15 extend through each ring 14 and thread into the respective boss 6 for securing the ring in chaser holding position. The chaser receiving slots or openings 12 are arranged in each boss 6 at the sides of or between the openings 2, 3 and 4 on account of the greater amount of stock in the bosses between said opening. This enables the bosses 6 to be of more shallow form and the head 1 to consequently be of smaller diameter as 80 the walls of the openings 2, 3 and 4 can then be made thin at points between each of such openings and the adjacent enlargements 5 of other openings as shown, as there is sufficient stock at the sides of the openings 2, 3 and 4 within the respective bosses 85 to accommodate the depth of the chaser receiving slots 12.

Each chaser 13 is of L-shape or has its inner threaded end portion provided at its outer edge with an ear to project outwardly within the ring 14, whereby the chaser is adapted to shoulder outwardly against the inner side of the ring to resist outward work-threaded pressure on the chaser. The inner work engaging ends of the chasers are backed by projections formed on the inner wall of the respective chaser receiving opening 5.

It is apparent that I have provided a 105 three-way thread cutting tool, which is light and compact in construction and is provided with a centering feature for the chaser

clamping ring of each seat, which is important to the practical and efficient operation of a tool of this character.

I wish it understood that my invention is not limited to any specific construction, arrangement or form of the parts as it is capable of numerous modifications and changes without departing from the spirit of the claims.

10 Having thus described my invention, what I claim as new and desire to secure by Letters Patent is:

1. A tool of the class described comprising a head having a plurality of bosses provided with substantially equidistantly spaced intersecting work-receiving openings disposed diametrically therethrough, one end of each opening being larger than the other, the surrounding wall of the large end of each opening being provided with radially disposed chaser-receiving recesses, an L-shaped chaser mounted in each of said recesses, and an element secured to the outer end of each boss for clamping the chasers thereto, said element being centered by the boss with respect to the axis thereof and a portion of said chasers projecting beyond the outer surface of said head to engage said element which element assists in counteracting the thrust of the chasers.

2. A compact three-way tool of the class described, having a head with a boss at each of three different sides thereof, the bosses being in circumferentially spaced relation around the head and each having an annular ring seat at its outer end with an annular shoulder at its inner edge concentric with the boss axis, said head having a diametrical opening therethrough for each boss with one end disposed within a respective boss in centered relation thereto and with

its other work centering end disposed between the two other bosses adjacent thereto, chasers mounted in each boss radially thereof and disposed between the adjacent work centering ends of the openings of the other two bosses and having their inner edges with respect to the axis of the head disposed in a plane which intersects the said adjacent openings, a chaser clamping ring mounted over the ring seat of each boss in centering engagement with the annular shoulder at the inner edge of such seat, and means for clamping each ring to its boss.

3. A die head having a work-receiving opening therethrough and formed with a flat annular seat at one end of the opening, an outwardly projecting annular flange at the inner edge of and concentric with the opening, said head having a radially disposed recess adjacent the work-receiving opening, a chaser in said recess, a clamping ring seating over the chaser for holding the latter in place and means for securing the ring to said head, said flange cooperating with said securing means for properly holding the ring in centered relation to the work-receiving opening.

4. A tool of the class described including a die head having a work-receiving opening therethrough and formed with a flat annular seat at one end of the opening, an outwardly projecting annular flange at the inner edge of and concentric with said opening, said head having radially disposed recesses adjacent the work-receiving opening for individually receiving chasers, said seat being adapted to receive a clamping ring which is held properly in centered relation by said projecting flange.

In testimony whereof, I have hereunto signed my name to this specification.

WILLIAM W. VOSPER.
